UNITED STATES PATENT OFFICE

JOHN J. FENTRESS, OF NORFOLK, VIRGINIA

SIGNAL DEVICE FOR SUNKEN VESSELS

Application filed March 11, 1929. Serial No. 346,147.

The object of this invention is to provide means whereby the crew of a sunken vessel can signal for help and also to provide means for marking the position of the sunken vessel.

5 This invention also consists in certain other features of construction and in the combination and arrangement of the several parts, to be hereinafter fully described, illustrated in the accompanying drawing and specifically 10 pointed out in the appended claim.

In describing the invention in detail, reference will be had to the accompanying drawing wherein like characters denote like or corresponding parts throughout the several 15 views, and in which:—

Figure 1 is a view showing the invention in use.

Figure 2 is a sectional view through the device, and showing the same in inoperative 20 position.

Figure 3 is a view showing the buoy in raised position, with the antenna in open position.

Figure 4 is a section on line 4—4 of Figure 3.

In these views, the numeral 1 indicates a cylinder which has its upper end opening out through the deck or other part of a vessel which is shown at A, the upper end of the 30 cylinder being normally closed by a hinged door 2 which is provided with a gasket 3 for making a watertight joint, the door being held closed by a latch 4 operable from inside the vessel. A buoy or float 5 is arranged in the cylinder and has a centrally arranged bore 6, the upper end of which is of reduced size, as shown at 6', and the lower end terminates short of the lower end of the buoy, though a 35 small hole 7 passes from the lower end of the bore through the lower end of the buoy.

The upper portion of the buoy is formed with the slots 8 which communicate with the bore and pass through the sides and top of the buoy. A member 9 is arranged in the 40 bore and has arms 10 thereon extending into the slots. Rods 11 are pivoted to the arms and extend upwardly through the slots, the upper portions of the rods engaging the pins 12 carried by the top part of the buoy and passing 45 through the slots. These pins act to hold

the rods in the position they occupy in Figure 2. A spring 13 is arranged in the lower part of the bore and acts to force the member 9 upwardly, though this member is held in its lowest position with the spring contracted by the door through means of a flagstaff 14, the lower end of which is fastened to the member 9 and its upper end is engaged by the door when the door is in closed position. The pennant or flag 15 is rolled and occupies 55 the reduced part 6' of the bore when the device is in the cylinder. A conductor cable 16 is connected with the lower end of the float and to the lower end of the cylinder, and this end of the cable is adapted to be suitably 60 connected with a radio sending set in the vessel.

From the foregoing it will be seen that if the vessel sinks, it is simply necessary for a member of the crew to release the latch 4 to 70 enable the pressure of the spring on the flagstaff to swing the door to open position and permit the float to rise to the surface. The spring 13 will push the member 9 upwardly until it reaches the upper end of the large 75 part of the bore, and as the rods 11 are connected with the member 9, these rods will open out to the position they occupy in Figure 3 and thus stretch the antenna wires 17 which are attached to the rods. The flagstaff 80 will also be raised to the position it occupies in Figure 3 and thus the buoy and the flag will act to indicate the position of the sunken vessel and the crew can radio appeals for help, as the antenna is electrically connected by the conductor cables 16 and the spring with the sending set in the sunken vessel.

In order to equalize the pressure in the cylinder with the pressure of the water exteriorly of the vessel, I provide a pipe 18 which connects the lower part of the cylinder with the exterior of the ship, and a smaller pipe 19 which connects the upper part of the cylinder with the exterior of the ship, each pipe having a valve 20 therein. Thus by opening the valves, sea water will enter the cylinder through the pipe 18 and air in the cylinder will escape through the pipe 19. Then when the cylinder is full of water, by opening the 100

latch 4, the spring can readily open the door so that the float can escape. If the float should fail to pass from the cylinder, it can be pushed therefrom by a rod 20 passing through a gland 21 in the cylinder, the inner end of the rod engaging the float.

Of course, a number of these devices can be placed on a ship, in different portions thereof, as shown in Figure 1, so that if a portion of the vessel carrying one of the devices is flooded, another of the devices can be used.

It is thought from the foregoing description that the advantages and novel features of the invention will be readily apparent.

15 It is to be understood that changes may be made in the construction and in the combination and arrangement of the several parts, provided that such changes fall within the scope of the appended claim.

20 What I claim is:—

In combination with a ship, a cylinder arranged in a part of the ship and opening out through a top portion thereof, a door for closing the cylinder, latch means operable from 25 inside the ship to hold the door in closed position, a buoy in the cylinder, an antenna carried by the buoy, a conductor cable connected with the buoy and electrically connected with the antenna, said cable being connected with 30 a part of the ship and electrically connected with a radio sending set in the ship whereby when the door is opened, the float will rise to the surface to mark the position of the sunken ship and enable the crew to radio appeals for 35 help, spring actuated means for opening the door when the latch is moved to releasing position, such means comprising a spring in the buoy, a member slidably arranged in the buoy and moved upwardly by the spring, a 40 flagstaff connected with the member and engaging the under face of the door, the antenna rods being connected with the member, guiding means on the buoy for the rods, such means normally holding the rods in folded 45 position and guiding them to open position when the float passes from the cylinder, means for admitting sea water into the cylinder before the door is opened and means for pushing the buoy from the cylinder if the same should 50 stick therein.

In testimony whereof I affix my signature.

JOHN J. FENTRESS.
